5. ATTORNEY

UNITED STATES PATENT OFFICE.

WILLIAM L. WILDE, OF BROOKLYN, NEW YORK.

BODY-PROTECTOR.

SPECIFICATION forming part of Letters Patent No. 317,693, dated May 12, 1885.

Application filed December 26, 1882. (No model.)

To all whom it may concern:

Be it known that I, WILLIAM L. WILDE, a citizen of the United States, residing at Brooklyn, in the county of Kings and State of New York, have invented a new and useful article of Gentlemen's Dress, of which the following is a specification, reference being had to the accompanying drawings, which are made a part thereof.

10 It is the object of my invention to provide an article of clothing for the protection of those parts of the body which most require it when exposed in severe weather, and which is also portable and may be readily and quickly applied to use and removed when no longer desired, and which so fits the body as to be convenient and comfortable in use and at the same time present to the eye the appearance of an ordinary well-fitting and comfortable 20 article of dress.

In the drawings, Figure 1 presents a front view of my invention, Fig. 3 a back view, Fig. 4 a perspective view showing the contour to fit the figure, and Fig. 2 a view of the 25 two halves when constructed in that form so as to be buttoned together.

Similar letters represent similar parts in all the figures.

A represents the body of my protector, which 30 is constructed in the form of a vest or waistcoat front and made so as to fit the contour of the body, as shown by the lines *d*, *e*, *f*, *g*, and *h* in Fig. 4. The body is constructed of cloth of proper material and texture to effect the 35 object sought and may be lined and wadded to suit the wishes of the wearer with respect to thickness and warmth. On this body A, which is cut so as to fit snugly around the neck, I place a collar, *a*, or produce the effect 40 of a collar without its actual existence by putting on binding *b*. This body may be made in one piece having buttons *i* and binding *k* up and down the center to represent the fronts of a vest buttoned together; or it may be made 45 in two parts, as shown in Fig. 2, and actually united together by buttons. Actual or imitation pockets may be made in or upon the body, as shown at *m*.

The upper part or portion of the body A 50 is cut so as to fit snugly to the neck or shirt-collar, and is provided with wings or shoulder-laps *n*, which, when the article is in use, are

held between the coat and waistcoat of the ordinary suit and serve very materially to hold the protector in place. The inner side 55 of the wings or shoulder-laps are lined with plush or its equivalent, to the end that the surface thereof resting upon the surface of the shoulder-pieces of the ordinary winter vest may assist in holding the adjustable vest in 60 position.

On the back of the body A near the top I place a large hook, *B*, (shown in Fig. 3,) which, passed over and behind the collar of the shirt, holds the protector in place there and prevents it from slipping down.

Buttons *q* and elastic *p*, the latter provided with a loop, *s*, provide a means of holding the lower part in place, if desired, by passing the elastic around the body and fastening it 70 to the button *q*. I provide a small pocket, *r*, near button *q* on one side, into which the elastic *p* may be put when not in use. A spring-catch, *t*, may also be used to hold the body in place at the bottom by thrusting it 75 behind the lap of the regular waistcoat, and it is obvious that other common and well-known devices may be attached to accomplish the same purpose.

The body might be held in place, when worn, 80 by small hooks *x* attached to the laps *n*, but I prefer the large hook attachment *B*, as above described.

I am aware that various improvements in gentlemen's apparel have been made, notably 85 in combined shirt-bosom supports and chest-protectors, also in combined vest and shirt fronts and in brick-layers' vests; but it has been my aim to construct an adjustable vest or waistcoat which could be quickly applied or 90 adjusted to the person without removing the ordinary coat or overcoat, and which could be as quickly removed without taking off the coat or overcoat, and which should be, when not in actual use, easily portable and convenient. It 95 is one of the obvious and principle advantages of my invention over all other improvements and appliances of kindred character that, while other appliances and inventions are applied either beneath the shirt, and therefore 100 necessarily become a part of the ordinary clothing of the body during the day, or are, by reason of having armholes, adjustable only by removing the coat and overcoat and so be-

come practically a fixed article of apparel, thus accustoming the body to their effect and affording neither special protection when going out into the cold air nor relief when entering a warm room, my invention secures warmth and instant protection when needed, and as quickly relieves the person from its effect when, on entering a warm room, it is removed.

Having thus described my invention, what I claim, and desire to secure by Letters Patent, is—

As a new article of manufacture, an article of gentlemen's clothing made in the form of a waistcoat-front consisting of the body A, so

cut as to conform to the person and fit snugly about the neck or shirt-collar, and having the shoulder-laps *nn*, lined with plush or its equivalent, and the hook B or its equivalent, the whole to be worn between the ordinary coat and vest and to be readily adjusted while the coat is on the wearer, and removed without the removal of the coat, substantially as shown and described.

WM. L. WILDE.
